UNITED STATES PATENT OFFICE.

LEO STEIN, OF ROCHESTER, NEW YORK, ASSIGNOR TO THE STEIN MANUFACTURING COMPANY, OF SAME PLACE.

DESIGN FOR A BURIAL-CASKET LID.

SPECIFICATION forming part of Design No. 17,227, dated March 29, 1887.

Application filed January 6, 1887. Serial No. 223,623. Term of patent 14 years.

To all whom it may concern:

Be it known that I, LEO STEIN, of Rochester, in the county of Monroe, in the State of New York, have invented new and useful Designs 5 for Metallic Burial-Casket Lids, of which the following, taken in connection with the accompanying drawings, is a full, clear, and exact description.

My invention relates to designs for metallic 10 coffin or burial-casket lids; and the invention consists in the herein-described design, which will be described in connection with the accompanying drawings, and pointed out in the claims.

15 Figure 1 is a top plan view of my newly-designed metallic coffin-lid. Fig. 2 is a transverse section taken on line $x x$, Fig. 1. Fig. 3 shows a top plan with the corrugations extending transversely across the lid; and Fig. 20 4 is a section taken on line $y y$, Fig. 3, these four views being deemed necessary to fully illustrate my design.

The leading feature of my design consists in the corrugated foot portion of the lid, the 25 same having the effect of stripes extending either lengthwise or crosswise of the foot portion in a straight line or curve, as best shown, in Figs. 1 and 3.

30 A represents the metallic lid, composed of the flat head-section B and the foot-section C, both sections having rounded ends $b c$ and a rim, d , extending around the entire edge of the lid.

The foot portion C has its surface corrugated with the parallel stripes $a a$, which may be 35 either V-shaped, oval, or semicircular in cross-section, and may extend either lengthwise or transversely across the foot portion, the object being to present a striped lid; and the corrugated surface may be either curved or flat, as 40 desired, and the ends $b c$ are rounded, as shown in Figs. 1 and 3, respectively.

Having thus fully described my design, what I claim as new, and desire to secure by Letters Patent, is—

45 1. The design for metallic burial-casket or coffin lids herein shown and described, consisting of the flat head-section with rounded end b , and the foot-section C, having a series of parallel raised corrugations, $a a$, substantially 50 as described.

2. The design for metallic burial-casket or coffin lids, consisting of the lid A, having a flat head-section, B, with rounded end b , foot-section C, having parallel corrugations $a a$, 55 and the rounded or circular end c , substantially as described.

In testimony whereof I have hereunto signed my name, in the presence of two attesting witnesses, at Rochester, in the county of Monroe, 60 in the State of New York, this 22d day of December, 1886.

LEO STEIN.
